DESIGN FOR A COMBINATION BRASSIÈRE AND PANTIE

Jules Chase, New York, N. Y.

Application May 28, 1935, Serial No. 57,050

Term of patent 14 years

To all whom it may concern:

Be it known that I, Jules Chase, a citizen of the United States of America, residing in Manhattan, county of New York, and State of New York, have invented a new, original, and ornamental Design for a Combination Brassière and Pantie, of which the following is a specification, reference being had to the accompanying drawing, forming part thereof, wherein,

Figure 1 is a front view of a combination brassière and pantie, showing my new design.

Figure 2 is a rear view of the combination brassière and pantie shown in Figure 1.

I claim:

The ornamental design for a combination brassière and pantie, substantially as shown.

JULES CHASE.
